UNITED STATES PATENT OFFICE.

ARTHUR RICHTER, OF BERGSDORF, ERZGEBIRGE, GERMANY.

DEVICE ON COTTON FRAMES FOR THE PRODUCTION OF BODILY THICKENINGS OF PATTERNS.

Application filed March 9, 1927, Serial No. 173,943, and in Germany December 1, 1926.

This invention relates to a device which makes it possible, to work bodily thickened patterns, especially leaf-shaped ones, into stockings as lengthened heel-reinforcement 5 on the cotton-frame. It has been proposed to provide at this point of the stocking some little pattern by giving a dented shape to the boundary lines of the reinforcement, but patterns in leaf-shape and the like could hitherto not be obtained for the reason, that it was impossible to produce the re-entering corners and arcs.

The device according to the invention is shown, by way of example, in the accompanying drawing in

Figs. 1 and 2 in front elevation mounted on one side of a cotton frame respectively in the position of rest and in the working position.

20 Fig. 3 is a side elevation of Fig. 2.

Fig. 4 shows a portion of a pattern-wheel with a thread-guide on larger scale.

Fig. 5 shows the finished portion of the stocking as it comes from the frame.

25 The commonly used abutment for the thread-guide is put out of working and consequently not shown in the drawing. For it is substituted a large pattern-wheel 1 having tappets, one pattern-wheel being rotatably mounted on each end of the cotton frame, so that the tappets 2 project towards the centre of the frame. As the pattern is composed of two portions I, II (Fig. 5), four thread guides 3 to 6 are provided, 30 besides the guides 7 and 8 for the base threads, and three of these thread guides co-operate with the tappets on the left-side of the frame, the three others co-operating with the tappets of the pattern wheel at the right 35 side of the frame.

40 In order that the tappets correctly limit the movements of the thread-guides the heads 9 on the tappets of the pattern-wheels are longer or shorter according to the pattern, so that they stand more or less distant from the pattern wheel, the thread-guide bars coming into contact with said heads 9. Each pattern wheel 1 is rotated one division after the knitting of one or several rows of 45 loops and in order that the heads 9 give way under the stroke of the thread-guide bars 3 to 8, the pattern-wheel 1 must be raised, when another tappet-head has to come in front of the thread guide-bar. The rotating 50 of the pattern-wheel is effected, uniformly

through one division, by means of a ratchet 10 and pawl 11. The engaging and disengaging of the eccentric 12, which raises the pattern wheel from the main shaft 13, is controlled from a pattern chain 14 which, at its two ends is mounted on the lower portion 60 of the machine and which, when travelling, brings pattern-buttons 15 under a lever 16. The lever 16 is thus lifted, so that it pulls aside the eccentric 12 in order that it gets 65 underneath a roller 17 mounted on a rod 18 and causes the rising of the pattern-wheel whilst, when no button 15 of the pattern chain stands under the lever 16, this lever remains in the lowered position, the eccentric 12 under the roller 17 of rod 18 being 70 pushed aside (Fig. 1) and does no longer act upon the pattern wheel. The pattern wheel executes every time only a part rotation, when the thickening from A to B (Fig. 75 5) is being produced and this according to the pattern, the pattern-wheel being raised every time and lowered by gravity.

At the production of the pattern (Fig. 5) the rotation begins at the beginning of the 80 thickening pattern at A and after one or two rows of loops have been knitted, the pattern-wheel is rotated and raised and brings another tappet-head in front of the 85 guide of the thickening thread, which is operated in the well known manner. When the thickening has been produced up to the point x a second thread guide is engaged for producing a thickening, and both 90 thread-guides find their tappets on the pattern-wheel which, after every row of loops, is rotated and raised in order to bring into position as abutment for the thread-guide-bars those tappets, which correspond to the pattern. The one thickening thread-guide produces the thickened edge-portion from x to 95 y and the second thickening thread-guide produces the inner portion x'. After the pattern has been completed up to y the second thickening thread-guide is disengaged 100 up to z, to be engaged again for producing the point z'. When the point z' is finished the second thread-guide is disengaged and the curve-portion is produced by the first thickening-thread-guide up to the heel-portion 105 with rotation and raising of the pattern-wheel. From this moment, when the heel-thickening has been finished the thickening ceases and the base-thread-guide knits in the well known manner the toe and leg of the 110

stocking until the heel-thickenings begin again. For the pattern-wheel a chain may be substituted which carries the tappets 2 and heads 9 and is raised and moved and lowered again.

I claim:—

A device on cotton-frames for the production of thickening-patterns, comprising in combination with the frame, with the main shaft and with an eccentric controlled from said main-shaft, several bars carrying guides for thickening threads, one pattern-wheel at each end of said frame, tappets having each a head and being short and long according to the pattern projecting from the inner sur-

face of each pattern-wheel and serving as abutments for said thickening-thread-guides, a pattern-chain controlled by said eccentric, means for raising said pattern wheel prior to each part rotation and means for communicating a part rotation to said pattern-wheel after the knitting of one or two rows of loops in order to bring said pattern wheel out of the range of said thread-guide-bars, so that it descends again by gravity to serve as abutment. 20 25

In testimony whereof I affix my signature.

ARTHUR RICHTER.

CERTIFICATE OF CORRECTION.

Patent No. 1,663,387.

Granted March 20, 1928, to

ARTHUR RICHTER.

It is hereby certified that error appears in the above numbered patent requiring correction as follows: In the grant and in the heading to the printed specification the residence of the patentee was erroneously written and printed as "Bergisdorf, Erzgebirge, Germany", whereas said residence should have been written and printed as "Berbisdorf, Erzgebirge, Germany"; and that the said Letters Patent should be read with this correction therein that the same may conform to the record of the case in the Patent Office.

Signed and sealed this 10th day of July, A. D. 1928.

M. J. Moore,
Acting Commissioner of Patents.
